E. W. DENMAN.

TIME SWITCH.

APPLICATION FILED JAN. 16, 1919.

1,433,704.

Patented Oct. 31, 1922.

UNITED STATES PATENT OFFICE.

EARL W. DENMAN, OF WILKINSBURG, PENNSYLVANIA, ASSIGNOR TO WESTINGHOUSE ELECTRIC & MANUFACTURING COMPANY, A CORPORATION OF PENNSYLVANIA.

TIME SWITCH.

Application filed January 16, 1919. Serial No. 271,464.

To all whom it may concern:

Be it known that I, EARL W. DENMAN, a citizen of the United States, and a resident of Wilkinsburg, in the county of Allegheny and State of Pennsylvania, have invented 5 a new and useful Improvement in Time Switches, of which the following is a specification.

My invention relates to time switches and 10 particularly to electrically-wound time switches.

The object of my invention is to provide a relatively simple and inexpensive time switch that shall have clock-control 15 means for winding the clock and actuating the switch.

In practicing my invention, I provide a clock mechanism, a motor and a spring-actuated snap switch. The motor is adapted to 20 be controlled by the clock mechanism for periodically winding the springs of the clock and the switch, and the clock mechanism is also adapted to control the operation of the switch. With this arrangement, accurate 25 operation of the clock may be ensured because the clock is not required to perform any undue amount of work but merely controls the motor and the switch.

Figure 1 of the accompanying drawings 30 is a front elevational view, with parts broken away, of a time switch embodying my invention, and Fig. 2 is a view taken along the line II-II of Fig. 1.

A time switch 1 comprises, in general, a 35 casing 2 in which is mounted a motor 3, a clock mechanism 4, a snap switch 5 and a controlling device 6. The casing 2 is provided with a cover member 7 for enclosing the same, and terminal members 8 are provided for operatively connecting the switch to the circuit (not shown) to be protected.

The clock mechanism 4 comprises an escapement device 9 and a spring 10 that is disposed in a spring barrel 11 and operatively 40 connected thereto at its outer end. The inner end of the spring 10 is connected to a shaft 12 upon which is mounted a gear wheel 13 and a sleeve member 14. A second sleeve member 15 is disposed around the 45 sleeve member 14 and is provided with a cam member 16 that may be actuated by a lever arm 17. Similarly, a cam member 18 is mounted on the sleeve member 14 and is adapted to be actuated by a lever member 50 19. The lever members 17 and 19 are pro-

vided with detents 20 that are adapted to engage the toothed periphery of an annular member 21 which is mounted on the shaft 12. The member 21 is divided, preferably, into 24 equal divisions representing the twenty four hours of the day. A stationary pointer 22 is mounted on a bracket 23 that supports one end of the shaft 12 and co-operates with the markings on the member 21 to indicate time. 65

The lever arm 17 is secured at 17^a to the sleeve 15. Upon movement of the arm 17 to a designated position on the periphery of the toothed member 21, the cam member 16, by reason of its connection to the sleeve 15, 70 is correspondingly moved. The engagement of the detents 20 of the arm 17 with the member 21 causes the cam 16 to be rotated with the member 21.

The cam member 18 is mounted on the 75 sleeve 14 and is connected to the toothed member 21 through the sleeve 14, arm 19 and the detents 20 of such arm. The cam members 16 and 18 may thus be adjusted relatively to one another and are rotatable 80 with the toothed member 21. This arrangement permits the cams to occupy the hereinafter described operative positions at any desired hour, depending upon the points at which the arms 17 and 19 are positioned 85 upon the toothed member 21.

A worm screw 24 is secured to the spring barrel 11 and is loosely disposed around the shaft 12. An internally screw-threaded cam member 25 is disposed on the worm screw 90 24 and has an opening therein to receive a pin 26 that is mounted in the gear wheel 13. A pin 27 is mounted on the cam 25 and is adapted to engage a pin 28 on the spring barrel 11, under predetermined conditions. 95 The gear wheel 13 engages a pinion 29 that is mounted on a spindle 30 upon which is also mounted a gear wheel 31. The gear wheel 31 engages a pinion 32 of the escapement device 9. 100

The switch 5 comprises a spindle 33 upon which is mounted a bridging contact member 34 and two cam members 35 and 36. One end of a spring 37 is connected to the bridging contact member 34 and the other 105 end is connected to a gear wheel 38 that is adapted to engage a gear wheel 39 on the spring barrel 11. The bridging contact member 34 is adapted to complete the circuit between stationary contact members 40 and 110

41, under predetermined conditions. Two lever arms 42 and 43 are pivotally mounted on a post 44 and are provided with hook portions 45, at the lower ends thereof, for controlling the operation of the switch 5. That is, the cam members 16 and 18 control the lever arms 42 and 43 which, in turn, control the switch 5 through the cam members 35 and 36 and, when the lever arms 42 and 43 are so actuated as to release the cam members 35 and 36, the spring 37 quickly actuates the switch 5 to its open or its closed position.

The ends 34^a and 34^b of the bridging member 34 lie in different horizontal planes, and the contact members 40 and 41 lie in the same horizontal planes as 34^a and 34^b, respectively. Thus, when the parts are in the positions indicated in Fig. 1, the contact members 40 and 41 are bridged, but when the bridging member 34 is rotated one-half of a revolution to break the circuit, and the cam or stop member 36 engages the lever arm 43, the end 34^a of the bridging member lies immediately above the stationary contact member 41 while the end 34^b lies below the stationary contact member 40.

A pinion 46 that is mounted on the shaft of the motor 3 engages a gear wheel 47 which, in turn, actuates the gear wheel 39 on the spring barrel through a gear wheel 48, a pinion 49, a gear wheel 50 and a pinion 51. A switch 52 for the circuit of the motor 3 comprises two co-operating pivotally mounted members 53 and 54 the member 53 of which is adapted to rest on the periphery of the cam 25. Thus, the switch 52 is adapted to periodically complete the circuit of the motor 3 and thereby wind the springs 10 and 37 a predetermined amount and, as the spring 10 is unwound by reason of the operation of the escapement device, the switch 5 is released and closed at predetermined times in accordance with the setting of the lever arms 17 and 19.

With the switch 52 in the position shown in Fig. 1 of the drawings, the motor 3 is energized to wind the spring 10 and, since the motor is connected to the spring barrel, the worm screw 24, that is also connected to the spring barrel, will be actuated and, since the pin 26 on the gear wheel 13 is substantially stationary, the cam 25 will not turn but will move towards the spring barrel 11 and thus the circuit of the motor 3 will remain closed until the pin 27 engages the pin 28. This will cause the cam 25 to be turned a sufficient amount to cause the member 53 of the switch 52 to assume the position shown in the broken lines in Fig. 1 of the drawings and thereby open the circuit of the motor 3. It will be understood that the pin 26 has sufficient play in the cam 25 to permit slight rotative movement of the cam 25 when the pins 27 and 28 are engaged.

When the switch 52 is opened, the motor 3 ceases to operate, and the escapement device 9 permits the spring 10 to be unwound and the shaft 12 to be actuated substantially as in a clock. However, since the lever arms 17 and 19 are placed in definite positions with respect to the member 21, the cam members 16 and 18 will release the lever arms 42 and 43 at predetermined times and thus permit the switch 5 to be actuated. As the spring 10 unwinds, by reason of the releasing of the same by the escapement device 9, the gear wheel 13 rotates and thus the pin 26 actuates the cam member 25 in a counter-clockwise direction which causes the same to move laterally along the worm screw 24. In other words, the member 53 of the switch 52 travels around the periphery of the cam 25 until it again is in such position as to engage the member 54 of the switch 52. This, of course, will again cause the motor 3 to operate and the springs 10 and 37 to be rewound. If the power that operates the motor is interrupted while the contact members 52 and 53 are in engagement, the pin 26 will turn the cam 25 to cause the same to move laterally along the worm screw 24, away from the spring barrel 11 a greater distance than it normally would should the power still be interrupted at the next winding period. Thus, it will require winding the spring 10 to a greater amount in order to again bring the pin 27 into engagement with the pin 28 to interrupt the circuit of the motor. This feature permits continued operation of the device should power be interrupted over a period greater than the period between normal windings.

A knurled-head device is provided for setting the member 21, as is the case in ordinary clock mechanisms.

With my invention, since the clock spring is not required to do any work except to control the motor and the switch, its operation may be exceedingly accurate.

I do not limit my invention to the specific structure illustrated, as it may be variously modified without departing from the spirit and scope of the invention, as set forth in the appended claims.

I claim as my invention:

1. In a time switch, the combination with a motor and a clock mechanism, of a spring-actuated snap switch provided with a spring adapted to contain stored energy sufficient to actuate the switch during a plurality of operations, means whereby the motor periodically winds the clock mechanism and the said spring, and means actuated by the clock mechanism for controlling the operation of the switch.

2. In a time switch, the combination with a motor and a clock mechanism, of a spring-actuated snap switch provided with a spring of sufficient capacity for a plurality of op-

erations, means whereby the motor periodically winds the clock mechanism and the said spring, and means actuated by the clock mechanism for controlling the operation of 5 the switch and the motor.

3. In a time switch, the combination with a motor, a clock mechanism, a switch and an actuating spring for the switch of sufficient capacity for a plurality of operations, 10 of means whereby the motor winds the clock and the said spring, and means actuated by the clock mechanism for controlling the operation of the switch and the motor.

4. In a time switch, the combination with 15 a motor, a clock mechanism and a spring-actuated snap switch, of means actuated by the clock mechanism for controlling the switch independently of the motor and for causing the motor to wind the clock spring 20 and the switch spring.

5. In a time switch, the combination with a motor, a clock mechanism and a spring-actuated snap switch that is provided with a spring of sufficient capacity for a plurality 25 of operations, of means whereby the motor may wind the clock and switch springs, and cam devices actuated by the clock mechanism for controlling the motor and the switch.

30 6. In a time switch, the combination with a motor and a clock mechanism, of a snap switch, a spring for actuating the switch, means whereby the motor periodically winds

the clock mechanism and stores energy in the switch spring, and cam members actuated by the clock mechanism for periodically opening and closing the switch and for controlling the operation of the motor. 35

7. The combination with a motor and a clock mechanism comprising a spring one 40 end of which is connected to the motor, an escapement device connected to the other end of the spring, a worm screw connected to the outer end of the spring, a cam member for engaging the worm screw, means connected to the escapement device for so turning the cam member that it moves laterally along the worm screw, a switch for the motor controlled by the cam member, and means connected to the outer end of the 45 spring for so actuating the cam member after the spring is wound that the switch is 50 quickly opened.

8. In a time switch, the combination with a motor, a clock mechanism, a switch, and 55 a spring for storing energy sufficient to actuate the switch during a plurality of operations, of means actuated by the clock mechanism for controlling the switch and for causing the motor to wind the clock spring and 60 the switch spring.

In testimony whereof, I have hereunto subscribed my name this 30th day of Dec., 1918.

EARL W. DENMAN.
